EXTENSION TRAY FOR A SHELF

Robert Jennee, Upper Saddle River, N.J., assignor to Electronic Assistance Corporation, Fair Lawn, N.J.

Filed Mar. 10, 1972, Ser. No. 233,867

Term of patent 14 years

Int. Cl. D6—04

U.S. Cl. D6—181

FIG. 1

FIG. 1 is a perspective view taken from the front, top and one side of an extension tray for a shelf, showing the new design;

FIG. 2 is a perspective view taken from the rear, top and side opposite that shown in FIG. 1, in disassembled relationship, a clip for mounting; and

FIG. 3 is a bottom plan view of the extension tray for a shelf.

I claim:

The ornamental design for an extension tray for a shelf, as shown.
